CLAIM

The ornamental design for a transport tray for spectacle lenses and spectacle lens blanks, as shown and described.

DESCRIPTION

FIG. 1 is a right side elevation view of the transport tray of our new design;

FIG. 2 is a bottom plan view of said transport tray of FIG. 1;

FIG. 3 is a rear side elevation view of said transport tray of FIG. 1;

FIG. 4 is a top plan view of said transport tray of FIG. 1;

FIG. 5 is a front side elevation view of said transport tray of FIG. 1;

FIG. 6 is a left side elevation view of said transport tray of FIG. 1; and,

FIG. 7 is a perspective view of said transport tray of FIG. 1.

The portions of the inlay for transport tray for spectacle lenses and spectacle lens blanks shown in broken lines form no part of the claimed design.
